METHOD OF PICKLING COILED METAL

Charles H. Manion, Follansbee, W. Va.

Application November 9, 1937, Serial No. 173,575

3 Claims. (Cl. 148—8)

This invention relates broadly to methods of pickling metal, and more particularly to a method of pickling metal which has previously been rolled into strip.

It is now common practice in steel mill operation to roll the steel into what is known as "continuous strip" comprising a single length of metal rolled into a continuous strip several hundred feet in length. The pickling of such a long length of strip is now commonly accomplished by threading the strip over and under alternately spaced rollers located within a pickling tank of considerable length. Pickling is accomplished by passing the sheet through the pickling bath contained within the tank or series of tanks. This method is objectionable because of the expensive equipment required and the extensive floor space needed for the tanks and apparatus. Other equipment designed for the purpose is also expensive.

It is the object of this invention to provide a method of pickling continuous strip steel which is simple, economical and efficient. The initial cost of the apparatus required to carry out the method is small; the maintenance and operation costs are comparatively negligible, and the installation and operation requires but a minimum of floor space.

Another object of the invention is to provide a method of pickling coiled continuous strip steel which depends principally upon natural forces for its successful operation, thereby eliminating the necessity for expensive and intricate mechanisms.

With these and other objects in view, the invention is hereinafter described, reference being had to the accompanying drawings, in which—

Figure 1 is a top plan view of a series of three pickling tanks in each of which is contained a plurality of coils of strip steel;

Figure 2 is a vertical sectional view taken on line 2—2, of Fig. 1;

Figure 3 is an enlarged side elevational view of two adjacent coils within a tank illustrating the coil opening action somewhat diagrammatically;

Figure 4 is an enlarged sectional view taken on line 4—4, of Fig. 2;

Figure 5 is an enlarged sectional view illustrating the construction and operation of the elevators whereby the coils are transferred from one tank to the next succeeding tank; and—

Figure 6 is a fragmentary top plan view of the tank at the coil discharge end depicting the disposition of the coil supporting bar.

Referring to said drawings, the reference numeral 10 designates generally a rectangular tank divided by partition walls 11 into compartments 12, 13 and 14. The tank 12 is intended to contain an acid solution; the tank 13 is intended to contain an acid solution weaker than that contained within the tank 12, and tank 14 preferably contains water. It may here be stated, however, that a plurality of separate and aligned tanks may be substituted for that shown in the 10 drawings.

Attached to the opposite side walls of each tank interiorly of the latter are inwardly directed and inclined ledges 15 designed to cooperate to serve as trackways on which the loosely coiled strip steel 16 may be supported with the coils disposed transversely of the tank. Spacing bars 17 are attached to the side walls of the tank at a spaced distance above and parallel with the trackways 15, the bars 17 functioning to space 20 the opposite ends of the coils away from the tank walls.

The lower ends of the trackways 15 terminate at a spaced distance away from the bottom of the partition walls 11. Located in this space is 25 a coil elevating and transferring mechanism consisting of a rectangular plate 18 having a concavity extending longitudinally in its upper face and having a length approximating the width of the tank. The under side of said plate 18 is 30 pivotally attached, as shown at 19, to a vertically reciprocable piston rod 20 penetrating the tank bottom and whose associated piston 21 is operable in a cylinder 22 located below the plane of the tank bottom. Forwardly extending projections 23 are provided on the plate 18 at a spaced distance from its opposite ends, and integral counterweights 24 extend rearwardly therefrom to overbalance the added weight of the projections 23 so as to return the plate 18 40 to its horizontal position after tilting.

In practice, a coil of strip steel, loosely coiled, is initially placed on the upper end of the trackway 15 transversely of the tank 12. As shown in Fig. 3 of the drawings, the self imposed weight 45 of the coil on its bottom side will cause the bottom convolutions of the coil to close while the convolutions of the segmental portion at the upper side will be spread apart. Thus, the opening of the upper convolutions enables the pickling fluid to have free and complete access to all exposed surfaces of the coiled strip.

Assuming that the lowermost coil within the tank 12 has been completely treated in said tank by the method now being explained and removal 55

therefrom is desired: The plate 18, on which said coil is supported, is elevated by actuation of the piston rod 20 and piston 21 by air, water, oil, or other suitable means introduced into the cylinder 22. Elevation of the plate 18 and the thereby supported coil is continued upwardly through the fluid bath until the plate reaches a point adjacent the top of the partition wall 11 where the projections 23 engage fixed projections 25 in said wall, whereupon continued elevation of the plate 18 results in the plate being tripped and tilted forwardly about its pivotal point, as shown in dotted lines in Fig. 5, causing the coil to roll off the plate and into the next adjacent tank. Following discharge of the coil, the plate 18 is returned to its horizontal position by the counterweights 24 and is downwardly retracted until it reaches the limit of its downward movement, at which point it is slightly below the plane of the lower end of the trackway 15.

During both the upward and downward movement of the elevating mechanism, the coils borne by the trackway 15 are maintained stationary by means of a cut-off plate 26, which latter is preferably fastened to and depends from the upper end of the piston rod 20 by means of a bracket 27. Said cut-off plate 26 is housed in an appropriately shaped cavity 28 provided therefor in the cylinder casing when the elevating mechanism occupies its retracted position. It will also be observed that the upper end of the cut-off plate 26 underlies the rear edge of the plate 18 and supports the latter in its horizontal position.

When the elevating mechanism reaches its fully retracted position, shown in full lines in Fig. 5 of the drawings, the line of coils, then being unsupported against forward movement, gravitate down the inclined trackway until the lowermost coil is supported by the plate 18. In so gravitating, the coils are rotated approximately 120° and the self imposed weight of each coil is consequently shifted so that the convolutions of a different segmental section of each coil are spread open, permitting free access of the pickling fluid to all surfaces then exposed. After a predetermined length of time, the then lowermost coil is elevated and transferred from the tank, as hereinbefore described, after which the remaining rolls again gravitate, the removed coil being replaced by a fresh coil at the top of the inclined trackway 15. Obviously, during the period between its introduction and discharge from each tank the entire surface area of the strip comprising the coil has been adequately subjected to the fluid bath. Moreover, it may be pointed out that the opening and closing of successive segmental sections of the coils with the consequent entrance and exit of fluid to different portions of the convolutions results in the fluid being more or less agitated, a condition deemed desirable for efficient pickling.

As will be understood, the coils are successively treated in the tanks 12, 13 and 14, the operation being completed in the latter. The elevating mechanism associated with the tank 14 differs

from the others in that its plate 18 is fixed to the piston rod and does not tilt. Upon reaching the limit of its upward movement, this particular elevating mechanism is adapted to be retained in that position until a rod 30, shown in Fig. 6, 5 is inserted axially of the coil. The elevator is then retracted and the ends of the rod 30 are engaged by U-bearings 31 attached to the opposite side walls of the tank interiorly of the latter. The coil is thus supported by the rod 30 from 10 which it may be unwound in continuation of the process of manufacturing strip steel.

The coils depicted in the drawings illustrate but a comparatively few convolutions. The coils so shown are for purposes of illustration only, and 15 it will be understood that numerous convolutions will be found in a coiled steel strip of several hundred feet in length.

What is claimed is—

1. The method of pickling continuous steel 20 strip in a tank containing the fluid bath, comprising the winding of the strip into a loose coil; positioning the coil on an inclined trackway extending through the fluid bath so that the coil supports its own weight thereon and thereby 25 spreads open the convolutions of an upper segmental portion of said coil so as to permit access of the fluid bath to all exposed surfaces of the open convolutions, and periodically permitting the coil to gravitate downwardly on the track- 30 way to intermittently rotate the coil to close the convolutions previously treated and to open others of successive segmental sections of said coil.

2. The method of pickling continuous steel 35 strip in a tank containing the fluid bath, comprising the winding of the strip into a loose coil, positioning a plurality of said coils on an inclined trackway extending through the fluid bath so that said coils support their own weight 40 on said trackway and thereby spreads open the convolutions of an upper segmental section of each coil so as to permit access of the fluid bath to all exposed surfaces of the open convolutions, and periodically removing the lowermost coil on 45 the trackway to permit the balance of the coils to advance by gravitation, thereby rotating each of the remaining coils a fraction of their circumference to close the convolutions previously treated and to open others for treatment.

3. The method of pickling continuous steel strip in a tank containing the fluid bath comprising the winding of the strip into a loose coil; positioning a plurality of said coils on a stationary, rectilinear trackway extending through the 55 fluid bath so that said coils support their own weight on said trackway and thereby spread open the convolutions of an upper segmental section of each coil so as to permit access of the fluid bath to the exposed surfaces of the open convolutions, and intermittently rolling said coils longitudinally on said trackway a fraction of their circumferences to move said coils forwardly 60 on the trackway and through the bath and to close said convolutions and open others for treat- 65 ment.

CHARLES H. MANION.
